JAMES WHELAN, OF BROOKLYN, NEW YORK, ASSIGNOR OF ONE-HALF TO HARRY L. SUTCLIFFE, OF NEW YORK, N. Y.

HEEL-SEAT-TRIMMING TOOL

Application filed May 24, 1927. Serial No. 123 940.

My present invention relates generally to shoe machinery, and has particular reference to a heel seat trimming tool.

Before describing my invention in detail, I will premise that in the manufacture of shoes, and particularly high-heeled ladies' shoes, it is customary to apply a strip of leather known as a "heel seat" to the bottom of the shoe before attaching the high heel thereto. The heel is generally made of wood, faced with a thin layer of the same leather which constitutes the upper of the shoe, and it is essential that the heel be applied in such a manner that nothing besides the heel facing and the shoe upper is visible after the shoe is completed. For this reason, the heel is provided with a concave upper surface, and the heel seat must be shaped accordingly to present a somewhat convex surface adapted to fit snugly into the concavity of the heel.

The initial trimming of the heel seat around its edges to impart thereto the convex surface mentioned is generally effected by a rotating cutter having a forward substantially conical operative face provided with a set of radially arranged cutting edges. In operation, the cutter is set into rapid rotation by means of a motor or the like, and it is then guided around the heel seat with the apex of the conical face traveling around the periphery of the heel seat.

The manufacture of the cutter results in the provision of an axial bore or opening at the apex of the cone, and in the operation of the cutter, the shavings which are thrown outwardly from the seat and hence toward the apex of the cone accumulate and fill in this axial bore. The accumulation of these shavings has been a great source of annoyance, inasmuch as they gradually become compressed and hardened and eventually clog the bore completely. As a result, the cutter's smooth and efficient operation becomes seriously impaired in a very short time, and unless the obstructing plug of hardened shavings is periodically removed—the removal of which entails a tedious and annoying series of steps—the cutter becomes practically useless for performing its contemplated purpose.

My present invention obviates these disad-

vantages, and one feature resides in the provision of a cutter which is so constructed and arranged that no lengthy accumulation and consequent compression and hardening of shavings is possible. Briefly, my invention 55 contemplates the provision of yieldable plugging or expulsion means in association with the bore so that the tool will be permitted to operate in its usual efficient manner and yet be constantly retained in clean and unclogged 60 condition.

In one embodiment, the plugging means comprises a plunger or core reciprocably mounted in the bore of the cutter and constantly urged outwardly by resilient means. 65 More particularly, a compression spring acts upon the rear end of the plunger and in this way renders the latter yieldably retractive during the cutting operation while at the same time any slight quantities of shavings 70 which may accumulate around the forward end of the plunger are automatically and positively expelled before any lengthy accumulation or hardening thereof can take place.

Another feature of my invention has reference to the contour of the operative blades or edges of the cutter. These edges are substantially radial but not truly so, extending in tangential directions from the periphery of the central bore referred to. The contour of 80 each edge has heretofore extended from this periphery in a gradual rearward and concave sweep. Accordingly, since the tool is guided substantially along the periphery of the heel being trimmed, the convexity imparted to the heel seat extends substantially to the edge thereof. As a result, it has heretofore been necessary to treat the heel seat further, even after the initial trimming thereof, so that the wooden heel may be made 85 to fit snugly thereon. This subsequent treatment is generally effected by a so-called "molding" machine whose operation forces a concave die upon the entire heel seat and thereby clears the extreme periphery of the 95 heel seat definitely and positively of any rough or raised portions which would interfere with the proper seating of the heel.

My present invention provides a cutter whose operative edges are so shaped that 100

the molding operation referred to may be entirely dispensed with. According to my invention, each edge of the cutter has its innermost portion arranged along a plane 5 perpendicular to the cutter axis. This construction also reduces the disadvantages heretofore encountered with respect to the accumulation of shavings in the central bore.

For the attainment of the foregoing objects and such other objects as may herein-after appear or be pointed out, I have illustrated one form of my invention in the accompanying drawings in which—

Fig. 1 is a side view of the rear portion 15 of a shoe prior to the trimming of the heel seat, the latter and an illustrative heel being shown in cross-section;

Fig. 2 is a view similar to Fig. 1 showing the heel in final position after the heel seat 20 has been trimmed;

Fig. 3 is an enlarged view, similar to Figures 1 and 2, showing the cutter and heel seat in operative relationship just prior to the cutting operation;

Fig. 4 is a view similar to Fig. 3, showing the cutter in cross-section and in operative relationship to the trimmed heel seat;

Fig. 5 is a diagrammatic plan view of a heel seat in process of trimming, the position of the cutter being shown in dotted lines, and the path of travel of the apex thereof being indicated in dot and dash lines;

Fig. 6 is a fragmentary cross-sectional view upon a greatly enlarged scale of the apex 35 of a cutter at the time of completion of a trimming operation; the cutter here shown being of the usual character; and

Fig. 7 is a view similar to Fig. 6 wherein a cutter embodying a feature of the present invention is shown.

The body of the shoe being manufactured is designated generally by the reference numeral 10, it being understood that this body is retained upon a suitable last throughout the operations hereinafter described. A thin strip of leather 11 is suitably affixed to the bottom of the shoe body, and after trimming thereof, in accordance with the steps hereinafter to be described, a heel 12 is eventually applied. It will be noted that the upper surface 13 of the heel (the surface eventually to be completely concealed) is concavely shaped, and accordingly, the heel seat 11 must be peripherally beveled or trimmed prior to the attachment of the heel so that the latter will eventually assume a position substantially as illustrated in Figure 2.

In Figures 3 and 4 I have illustrated the heel seat trimming tool which may comprise a spindle 14 suitably rotated by a motor or the like (not shown), and a rotatable cutter 15. The spindle 14 is provided with a collar 16 and an end portion 17 of reduced di-

ameter and externally threaded to receive the cutter 15 thereon in a removable manner.

The cutter has an internally threaded bore 18 extending from the rear surface thereof, the threads being adapted to engage the threads of the end portion 17 as shown in Figure 4. In the form here shown, the forward or operative face of the cutter 15 is substantially conical in shape and comprises a series of radially arranged cutting edges 19, the contour of each blade being constructed in accordance with the particular convexity desired upon the heel seat to be trimmed. Extending inwardly along an axial line from the apex of the cone is a bore or opening 20, considerably smaller than the main bore 18 but communicating therewith and merging therewith by the conical surface 21. The outer mouth of the bore 20 is conically shaped, as indicated more clearly in Figure 6, and the edges 19 extend rearwardly in a concave sweep from the periphery of the bore 20.

In the end of the spindle 14, I have provided an axial bore 22 substantially equal in diameter to that of the bore 20. Into the bore 22 I insert a small coil spring 23, and on top of this spring a plunger 24 is inserted of sufficient length to extend also into the bore 20. The inner end of the plunger 24 is preferably attenuated to provide a support for the spring 23.

The plunger 24 is provided with a collar 25 between the bores 20 and 22, this collar limiting the reciprocating movability of the plunger by encountering either the front face of the projection 17 or the conical surface 21. The plunger and collar are so constructed that the forward rounded tip of the plunger will just barely project out of the bore 20, as shown in Figure 3 and in dot and dash lines in Figure 6 when the tool is not in use. Furthermore, the retractive movement of the plunger is arranged to be limited so that the forward portion of the plunger will in no event be withdrawn inwardly out of the bore 20.

In operation, the cutter 15 is mounted upon the spindle 14 and the latter is set into rapid rotation by means of a motor or the like. Suitable mechanism is provided for guiding the rotating spindle and cutter bodily along a predetermined or desired path. This guiding mechanism comprises an adjustable plate having a substantially U-shaped slot therethrough. This plate is not illustrated, but is arranged in association with the upper end of the spindle 14. At this upper end, a collar is mounted upon the spindle 14, and the slot is of a width co-extensive with the diameter of the collar so that the movement of the spindle will be defined by the slot. The shoe body bearing the heel seat to be trimmed is suitably clamped in the inverted position illustrated in the

drawings, and to protect the upper of the shoe body, a metallic plate or wiper 26 is wedged beneath the heel seat 11 around the periphery thereof. It will be understood that the wiper 26, forming no part of the present invention, may be of any suitable or usual construction or design, and will probably comprise at least two cooperating plates, suitably shaped and movable, to protect the upper of the shoe around the entire periphery of the heel seat.

The rotating tool is then brought into operative relationship with respect to the heel seat, and is guided in an arcuate or U-shaped path substantially as indicated by the dot and dash line 27 of Figure 5. It will be noted that the apex of the conical operative face of the tool is guided along a line substantially coincident with, or closely skirting, the periphery of the heel seat. During this guided movement of the cutter, a bevel 28 is imparted to the heel seat, and it will be understood that this operation may be effected in a very few seconds because of the rapid rotation of the cutter and by virtue of the suitable slot guide means for the spindle.

Reference to Figure 4 will clearly show that the complete trimming operation necessitates a retractive movement of the plunger so that the forward tips of the edges 19 and the forward rounded tip 29 of the plunger lie in substantially the same plane. The fine shavings produced by the operation of the cutter and thrown outwardly toward the peripheral path of travel of the cone apex have heretofore accumulated in the bore 20, but in accordance with the present invention, no room is afforded for any accumulation other than a slight amount in the space between the plunger tip 29 and the extreme outer portion of the bore 20. If the plunger were permanently fixed in the position of Figure 4, even this slight accumulation of shavings would in a very short time produce the same disadvantageous effects that have heretofore been encountered. Inasmuch as the plunger is reciprocably mounted, however, and inasmuch as its normal position is the one shown in Figure 3 and in dot and dash lines in Figure 6, wherein it projects slightly from the bore, whatever shavings may have accumulated are automatically and positively expelled after each operation of the tool. In other words, after each heel seat has been beveled or trimmed, the entire spindle is removed from the shoe body to permit the withdrawal of the latter and the substitution of a succeeding untrimmed heel seat; and as the spindle and cutter are thus withdrawn, the spring 23 exerts its outwardly pressing force to project the plunger into its normal forward position, thereby ejecting whatever shavings may have accumulated around the tip 29. As a result of

this automatic ejection, the tool is rendered efficiently operative for each cutting operation, and any changing of cutters for purposes of cleaning is rendered wholly unnecessary.

It will be understood that the phase of my invention heretofore described in greater detail, i. e., the phase which relates to the movable plunger, is quite independent of the other phase of my invention which I shall presently describe.

In Figure 7, I have shown a cutter 15' provided with a cutting edge whose innermost portion 30 is perpendicular to the axis of the cutter. The edges of the cutter 15' therefore define or lie in the surface of a substantially truncated cone. The provision of a cutter of this character permits the elimination of the conical end portion of the bore 20 and accordingly reduces the small space around the tip 29 of the plunger wherein shavings accumulate. The provision of such a cutter also enables the molding operation heretofore performed upon initially trimmed heel seats to be entirely dispensed with. For the purpose of clearly depicting the latter advantage, I have shown the cutters of Figures 6 and 7 in similar positions with respect to wipers 26 and 26' and shoe uppers 31 and 31'. It will be noted that the heel seat 11 of Figure 6 embodies a convexity which extends further toward the edge of the heel seat than the convexity of the heel seat 11' of Figure 7. The heel seat 11 of Figure 6 will probably have to be molded in order to accommodate the close application of the wooden heel; whereas no such molding operation will be necessary with respect to the heel seat 11'.

Although I have illustrated and described my invention as applied to a cutter for trimming or beveling heel seats, nevertheless it will be understood that an application of this character is not essential. Furthermore, I do not mean to limit myself to the particular type of plunger illustrated and described, the shape and arrangement of the plunger and spring means being variable to suit varying requirements. In general, it will be obvious that many changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. In a trimming tool of the character described, a spindle having an axial bore in its end, a spring in said bore, an end-thrust cutter detachably applicable to said end to rotate with the spindle, said cutter having an

axial bore therethrough, and a plunger reciprocably mounted in said bores and urged outwardly by said spring.

2. In a trimming tool of the character described, a spindle having an axial bore in its end, a spring in said bore, an end-thrust cutter detachably applicable to said end to rotate with the spindle, said cutter having an axial bore therethrough, a plunger reciprocably mounted in said bores and outwardly urged by said spring, and a shoulder arranged on said plunger between said bores for limiting the reciprocal movement of the plunger.

3. A heel seat trimming tool of the character described comprising a rotatable cutter whose forward operative surface is provided with a series of substantially radial cutting edges, each edge having its innermost portion perpendicular to the axis of the cutter, and the balance thereof concaved, whereby there may be imparted to a heel seat a contour which is marginally plane and otherwise convex.

25 In witness whereof, I have signed this specification this 23 day of May, 1927.

JAMES WHELAN.
